OPHTHALMIC MOUNTING

Gerhard A. Ellestad, Rochester, N. Y., assignor to
Bausch & Lomb Optical Company, Rochester,
N. Y., a corporation of New York

Application February 1, 1935, Serial No. 4,532

7 Claims. (Cl. 88—47)

This invention relates to ophthalmic mountings and more particularly it has reference to connecting means which are used for securing together the various parts of an ophthalmic 5 mounting.

One object of my invention is to provide an improved connecting means for ophthalmic mounting parts. Another object is to provide locking means for detachable retaining elements 10 on ophthalmic mountings. A further object is to provide a movable member which may be selectively moved into or out of locking engagement with the screw on an ophthalmic mounting. A still further object is to provide an article of 15 the type described which will be simple in structure, neat in appearance and efficient in operation. Still another object is to provide improved means for detachably securing a lens in an ophthalmic mounting. These and other objects and 20 advantages reside in certain novel features of construction, arrangement and combination of parts as will hereinafter be more fully described and pointed out in the appended claims.

Referring to the drawing:

25 Fig. 1 is a front view of an ophthalmic mounting embodying my invention.

Fig. 2 is a sectional view thereof showing a tool 30 adapted to move the locking member.

Fig. 3 is a similar view of a modification.

35 Fig. 4 is a view of the inner face of the rear strap of same with parts in section.

A preferred embodiment of my invention is 40 illustrated in the drawing, as applied to a lens mounting, wherein 10 indicates a member having the spaced front and rear straps 11 and 12, respectively, positioned on opposite faces of the lens 13. The member 10, having the usual shoe 14 extending along the edge of the lens, is soldered to the bridge member 15. The screw 16, 45 passing through the opening 17 in the lens 13, threadedly engages the rear strap 12 and thus connects the front and rear straps.

The inner face of the rear strap 12 is provided 50 with a recess 18 in which is movably mounted a flat resilient member 19 having an opening 20 through which the screw 16 passes. One end of the resilient member 19 is secured to the strap 12 by means of the screw 21 so that the member 19 normally occupies the full line position shown 55 in Fig. 2. With the screw 16 in place, one edge of the opening 20 of member 19 will normally be in contact with the screw at 22 so as to lock the latter against rotation. In order to move the member 19 out of locking engagement with the screw, the member 19 is moved down to the

dotted line position of Fig. 2 by means of a pin 23 which is inserted through hole 24 in strap 12. In this position of the locking member 19, screw 16 passes freely through the opening 20 so that the screw may be readily withdrawn or inserted 5 in the usual manner. It will thus be apparent that the resilient member 19 provides means for locking the screw 16 against rotation but that the member 19 may be selectively moved out of engagement with the screw in order to permit a 10 free insertion or withdrawal of the screw.

In the modification shown in Figs. 3 and 4 the rear strap 12 has formed on its inner face the recess 25. Slidably mounted within the recess 25 is the locking member 26 which is retained loosely by a screw 27 cooperating with a slot 28 to permit free sliding movement of the member 26. The member 26 is provided with an opening 29 through which passes the screw 16. The opening 29 has a tapered portion 30 which is adapted to be forced into wedging engagement with screw 16 by sliding the member 26 by means of a pin 31 which passes through the aperture 32 on member 26. In this position, the member 26 serves as a lock to 20 prevent rotation of the screw 16. The member 26 may be moved out of locking engagement with the screw 16 by inserting the pin 31 through aperture 33 so as to engage the upturned part 34 on member 26. 30

From the foregoing it will be apparent that I am able to attain the objects of my invention and provide relatively simple, yet efficient, connecting means for ophthalmic mountings. A mounting embodying my invention is neat in 35 appearance as the movable locking members are concealed. Although I have illustrated my invention as applied to means for mounting lenses it is obvious that it may be equally well adapted for locking screws which are used for other purposes on ophthalmic mountings. Various modifications may be made without departing from the spirit of my invention. 40

I claim:

1. An ophthalmic mounting comprising a part, 45 a retaining element detachably secured to said part for holding together a plurality of ophthalmic mounting devices, a member having one end fixedly mounted on said part, said member having a movable part provided with an aperture 50 through which said element extends, said member being resilient and constructed so that the wall of said aperture is normally urged into locking engagement with said element.

2. In an ophthalmic mounting, the combina- 55

tion of a strap positioned on the face of a lens having an opening, a retaining element positioned in said opening and secured directly to said strap, a locking member movably mounted on said strap, 5 said member having a hole within which said element is positioned, and coacting locking means on said element and on the wall of said hole, said member being adapted to be selectively moved to bring the locking means on the wall of the hole 10 into or out of locking engagement with the locking means on the element.

3. In an ophthalmic mounting, the combination of a strap positioned on the surface of a lens having an opening, a retaining element positioned 15 in said opening and secured directly to the strap, said strap having an internal recess formed on its inner face, a locking member movably mounted within said recess, coacting locking means on said element and said member, said member being 20 constructed and arranged to be selectively moved into or out of locking engagement with said element, said strap having an aperture in the wall of said recess whereby said member may be moved by means of a tool inserted through the aperture. 25

4. An ophthalmic mounting comprising a part having two spaced straps positioned on opposite faces of a lens having an opening, a screw connecting said straps and positioned in said opening, one of said straps having a recess formed 30 on its inner face, a member slidably mounted within said recess to move in a plane substantially perpendicular to the axis of the screw, said member having a slot through which said screw extends, and means permitting selective movement of said member, into or out of locking engagement with said screw. 35

5. An ophthalmic mounting comprising a strap adapted to be positioned on the surface of a lens having an opening, a screw passing through said

opening and threaded to said strap, said strap having a recess formed on its inner face, a resilient member mounted with one of its ends free to move in said recess, the free end of the member having an aperture through which said screw extends, the wall of said aperture being normally urged into locking engagement with said screw, said strap having an opening leading into said recess whereby said member may be selectively moved out of locking engagement with said screw. 10

6. An ophthalmic mounting comprising a part having a strap adapted to be positioned on the surface of a lens having an opening, the inner side of said strap having a depression facing the surface of the lens, a locking member movably mounted within said depression, said member having an aperture, a retaining element passing through said aperture and positioned in said opening and secured directly to said strap, said member being constructed and arranged to be selectively moved into or out of locking engagement with said element, the movement of said member being confined entirely to said depression, said strap having a relatively small aperture leading into said depression whereby a tool may be inserted in said depression for moving said member. 15 20 25

7. An ophthalmic mounting comprising a part having a strap adapted to be positioned on the surface of a lens having an opening, the inner side of said strap having a recess, a retaining element passing through said opening and recess and secured to the strap, a resilient member having one end secured to the strap and the free end movable within said recess, said member having a part normally urged into locking engagement with said element by the resilience of said member. 30 35
